UNITED STATES PATENT OFFICE

WALTER A. KRENTLER, OF DETROIT, MICHIGAN, ASSIGNOR TO KRENTLER-ARNOLD
HINGE LAST COMPANY, OF DETROIT, MICHIGAN, A CORPORATION OF MICHIGAN

LAST

Application filed September 14, 1927. Serial No. 219,408.

This invention relates to a shoe last and more particularly to a hinge construction for lasts wherein the heel part and the toe part may be relatively turned to collapse the last for its insertion and withdrawal from the shoe.

An object of the present invention is to provide a very simple, strong and rigid device for connecting the last parts, which device is such as to firmly hold the parts together and take up wear, thereby obviating the necessity for other positive pivotal connection between the last parts to prevent their separation or disalignment, and which device embodies separate members connected by yielding means arranged to exert a force tending to shorten the over-all length of the device by moving said members relatively in opposite directions.

A further object is to provide a connecting device which will lend relative lateral rigidity to the last parts, and the construction of which is such as to reduce the liability of breakage to a minimum and facilitates assembly. A further object is to provide a device for the purpose which will require the cutting away for its insertion, of but a minimum part of the last body and which may be constructed of steel stampings or punchings, thereby reducing the cost of manufacture and increasing its strength. It is also an object to so mount the device relative to the knuckle connection of the last parts as to offer resistance to relative turning movement of the parts from their extended or collapsed positions and to secure last strength and rigidity by connecting the ends of said device at a distance from the last knuckle and well within the thick body portion of each last part. A further object is to secure the several advantages inherent in the construction all as hereinafter more fully set forth.

With the above and other ends in view the invention consists in providing connecting members having overlapped adjacent ends with said ends connected together by yielding means tending to move said members relatively in a longitudinal direction and shorten the over-all length of the device, thereby exerting a force to hold the last parts in firm

contact while permitting relative turning movement. The invention further consists in the construction and arrangement of the connecting device, and in certain other new and useful features, all as hereinafter set forth and more particularly pointed out in the appended claims, reference being had to the accompanying drawing, in which

Figure 1 is a side elevation of a last illustrative of an embodiment of the present invention, and showing portions of the last broken away and in section to more clearly disclose the invention;

Fig. 2 is a view similar to that of Fig. 1 and showing the last in collapsed position;

Fig. 3 is a horizontal section substantially upon the line III—III of Fig. 1;

Fig. 4 is a sectional detail showing a slightly modified construction, and

Fig. 5 is a section upon the line V—V of Fig. 4.

Hinged lasts, or lasts embodying a pivotal connection between their heel and toe portions, are usually connected by members which require the cutting away of large portions of the wood of the heel and toe parts, thus weakening these parts. In order to withstand the heavy pressures applied to the last during the leveling, heelng, and truing operations in the manufacture of shoes by present day methods, it is very important that the last parts be cut away to a minimum extent, so that the insertion of the means for hinging said parts and holding them firmly together in all of their relative positions, will not weaken the last body and cause splitting or cracking of the wood under such strain. It is also imperative that the last parts be pressed toward each other and rigidly held against relative lateral or twisting movement, and that the means connecting the parts offer sufficient resistance when the last is extended, to prevent collapsing or partial collapsing during pulling over and lasting operations.

This connection must therefore be very strong and rigid in order to take the strains to which it is subjected, and should be simple in construction to facilitate assembly and take up a minimum of space in the last body.

The last construction may be simplified by providing means for connecting the last parts, which means will continuously exert a force tending to hold said parts in firm contact with each other, as by this arrangement, the connecting pintle or other pivot member may be dispensed with and one part of the last, such as the toe part 1, may be formed with a socket 2 and the other part, or heel 3 formed with a knuckle 4 to fit into the socket, this being a simple, well known form of last.

The device for connecting and holding the last parts in firm contact, with the knuckle 4 or one part firmly seated in the socket 2 in the other part, comprises preferably, a link 5 and a pair of links 6 with the end portion of the link 5 interposed between the adjacent ends of the links 6 and with the overlapping ends of all of the links formed with alined holes to receive a volute spring 7 which is formed by rolling a strip of spring steel lengthwise upon itself into a cylindrical coil of width to extend through the openings in all of the links with the edges of the strip flush with the outer surfaces of the links 6. This coil is of greater diameter than the diameter of the holes in the links and is therefore compressed slightly when inserted, thus by its tendency to expand diametrically, holding the links yieldingly with their openings alined. The opposite or free outer ends of the links are formed with openings to receive pivot pins 8.

The toe portion 1 of the last is formed with a cut or recess 9 centrally of the body of said portion and extending well forward into said body and the heel portion 3 is also formed with a vertical cut or recess 10 in longitudinal alinement with the cut 9 and extending transversely of the knuckle 4 and into the body of the heel portion. These cuts 9 and 10 are of a width transversely of the last, substantially equal to the over-all thickness of the assembled links 5 and 6 so that said links will fit within said cuts or recesses and be guided laterally against tilting or twisting movement thereby. These cuts are, however, of a width and shape vertically of the last to permit of the free swinging movement with these cuts, of the connection formed by these links, when the heel portion is turned upon its knuckle relative to the toe portion.

The connecting links 5 and 6 are first assembled as described, by inserting the spring 7 within the alined openings in the overlapped ends of the links thus forming a connecting unit, and the last is then assembled by placing this connecting unit within the cuts 9 and 10 provided to receive the same, and the pins 8 are then driven into transverse openings 11 in the heel and toe portions through the openings in the free ends of the links, said holes 11 being so located that the

driving in of the pins will further compress the spring 7 which will thus exert a force to yieldingly hold the knuckle of the last part firmly seated in its seat on the toe part. Further, these holes to receive the pins 8 are so located relative to the axis of turning of the knuckle in its seat, that when the heel part is in extended position, as shown in Fig. 1, a line connecting the centers of pins 8 will lie below said axis, and when the heel part is in the position shown in Fig. 2, said line will be above said axis. Therefore in swinging from one position to the other, the distance between these pin centers must increase as the connection swings past the center of the knuckle, the spring being compressed slightly to allow for such increase, and thus the spring exerts a yielding force to hold the heel portion turned to the limit of its movement in either direction, as well as to constantly force the knuckle yieldingly toward its seat at all times. This arrangement of pivotal connection relative to the turning axis of the last parts, is disclosed broadly in my United States Patent numbered 1,094,153 of April 21, 1914.

In Figs. 4 and 5 a modified construction of connecting means between heel and toe portions of the last, is shown, said modified construction comprising a pair of link members 12 and 13, each formed with a longitudinal slot intermediate its ends, said slots being formed by cutting the metal along parallel lines, and at one end of the slot, and striking out the severed portion laterally to form an integral lug 14 at one end of each slot. The two links or parts are then placed with the lug on one link projecting into the slot of the other link so that the two links are held in alinement but free to slide relatively in a longitudinal direction. A coiled spring 15 is then inserted in the slots between the lugs and under compression so that said spring will exert a force at all times tending to move the links relatively and shorten the over-all length of the device. The two links may move relatively against the action of said spring and when assembled in the last parts in the same manner as previously described, said spring will yieldingly hold the knuckle of the heel part seated in the socket of the toe part and will yield to permit the swinging of the heel relative to the toe as the connection swings from one side to the other of the pivotal axis of the last parts, as disclosed generically in my patent numbered 1,094,153 above referred to.

A connecting device of this character is very simple in construction and cheap to manufacture, and being formed of steel stampings or the like is very strong and rigid. The construction further lends itself to assembly in a last as a unit and in a manner precluding breakage in use, giving long life to the last, the parts of which are firmly held

thereby in firm contact with each other and against lateral or twisting movement.

Changes in the details of construction and arrangement to suit the type of last used and to conform to other conditions of use, are contemplated and I do not therefore, limit myself to the particular construction shown.

Having thus fully described my invention what I claim is:

1. The combination with a last comprising a toe part formed with a socket and a heel part formed with a knuckle to seat in said socket, of a connecting device comprising a pair of link members having overlapping adjacent ends movable relatively in a longitudinal direction and openings at their outer ends, yielding means connecting the overlapping ends of the members and under compression to move said members relatively in opposite longitudinal directions, said heel and toe parts of said last being formed with alined recesses extending into the body of the parts and transversely of their knuckle joint connection, said recesses being of a width transversely of the last substantially equal to the thickness of the connecting device when in place within said recesses, and pivot pins extending transversely of the heel and toe parts and through the openings in the outer ends of the members of the connecting device to secure said connecting device to said last parts, said pins being so located relative to the knuckle axis of the last as to swing said connecting device from one side to the other of said axis when the last parts are turned relatively and further compress said yielding means during such swinging movement.

2. A connecting device for hinged lasts including a plurality of link members having overlapping adjacent ends and formed with openings in said overlapping ends, and yielding means within said openings forming the whole connection between said members and exerting a force tending to move said members relatively in a longitudinal direction and to hold the last parts in yielding contact with each other.

3. A connecting device for hinged lasts including link members having overlapping adjacent ends formed with alined openings, said members being also formed with pivot openings at their opposite ends, and a flat spring coil inserted in said alined openings with its axis extending transversely of said overlapped ends and under compression for yieldingly connecting said ends of the members.

4. A connecting device for hinged lasts including a spring coil of cylindrical form, and a plurality of relatively movable members pivotally connected to the last parts and arranged to compress said spring in a direction transversely of its axis by relative movement of said members upon turning movement of the last parts, said spring being carried by

said members and unsecured to said last parts.

5. A connecting device for hinged lasts including members pivotally connected to the last parts at their outer ends with their adjacent ends overlapped and provided with openings, and a volute spring coiled to exert a radial expansive force and confined in said openings to normally hold said members with said openings in axial alinement.

6. A connecting device for hinged lasts including members having overlapping ends formed with openings, a coil formed of flat spring material of a width to extend through said openings in said overlapped ends and connect said members, said coil being confined within said openings by its radial expansion and arranged to be radially compressed by relative endwise movement of said members.

7. A hinge adapted for uniting parts of pivoted last together, comprising a member adapted to be pivotally secured to one part of the last, a second member adapted to be pivotally secured to the other part, said two parts having recesses therethrough adapted to receive a uniting element, and a curved plate spring fitted within said recesses to unite said last parts and permit a relative yielding movement therebetween.

8. A last comprising a fore part and a heel part adapted for relative pivotal movement upon a transverse axis, and means for connecting said last parts pivotally connected to said fore part laterally of said axis and to said heel part laterally of and at the opposite side of said axis, for swinging movement in a plane at right angles to said axis and across said axis as said last parts are turned relatively, said connecting means embodying an element adapted to yield to increase the overall length of said means as the same swings across said axis in the turning of said last parts relatively.

9. The combination with a last having a toe part and a heel part pivotally connected for relative turning movement upon a transverse axis, of means for connecting said last parts including members pivotally connected at their opposite ends to the last parts at opposite sides and laterally of said axis to extend transversely of said axis and swing thereacross upon relative turning of the last parts upon said axis, and yielding means connecting the adjacent ends of said members and adapted to yield as said members swing from side to side of said axis across the same.

10. A connecting device for hinged lasts including longitudinally aligned link members formed with openings in their remote ends to receive pivot pins for connecting said members to the heel and toe parts of the last at opposite sides of the axis of the pivotal connection of said parts, and a spring member connecting the adjacent ends of the links and exerting a force thereon tending to normally

move the links toward each other and draw the last parts into contact.

11. A last having a fore part and a heel part, adapted for movement relative to each other, a hinged member secured to one part, a second hinged member secured to the other part, said hinged members being free to move relatively in a longitudinal direction, and yielding means connecting the adjacent ends of said hinged members and exerting a force thereon to move said members relatively and said last parts toward each other.

12. A last having a fore part and a heel part adapted for pivotal movement relative to each other upon a transverse axis, means uniting said last parts comprising members yielding connected at their adjacent ends and pivotally connected at their opposite ends to said heel part and fore part at opposite sides of said axis to swing upon their pivotal connections to said last parts and move from side to side across said axis upon turning movement of said parts upon said axis.

In testimony whereof I affix my signature.

WALTER A. KRENTLER.
